CLAIM

The ornamental design for a L-shaped rail assembly for holding a fence panel, as shown and described.

DESCRIPTION

FIG. 1 is a perspective view of an L-shaped rail assembly for holding a fence panel.

FIG. 2 is a front elevational view thereof.

FIG. 3 is a rear elevational view thereof.

FIG. 4 is a side elevational view thereof.

FIG. 5 is another side elevational view thereof.

FIG. 6 is a top plan view thereof.

FIG. 7 is a bottom plan view thereof; and,

FIG. 8 is a perspective view of the L-shaped rail assembly for holding fence panel in condition of use with a section of fence and an additional rail assembly shown in broken lines. The broken lines in FIG. 8 illustrate environmental structure and an additional rail assembly that form no part of the claimed design.
